MACHINE FOR INTRUSIVELY PUNCHING

Frank Jermain Chandler, Toledo, Ohio, assignor
to The Perfotex Company, Toledo, Ohio, a cor-
poration of Ohio

Application June 8, 1936, Serial No. 84,024

1 Claim. (Cl. 164—89)

This invention relates to machines or apparatus for perforating materials, but more particularly to machines for and methods of intrusively perforating relatively thick and tough materials, such as rubber coated textile fabrics or other similar composite materials.

Heretofore, machines and apparatus have been devised for intrusively perforating composite materials including rubber or rubber like material, but they have not proved entirely satisfactory because they are not adapted to perforate relatively thick materials of this nature expeditiously and economically on a production basis and to provide sufficient and adequate perforations of a minute nature to impart the "breathing" characteristic so necessary and desirable in materials used for shoes, clothing, corsets, etc.

It is a desideratum to produce a simple and efficient method of and machine for perforating a relatively large amount of material of this nature in a comparatively short time and to position and arrange the perforations closely together in an irregular, non-mechanical appearing manner, to resemble or simulate as closely as possible the pores of the skin.

An object of this invention is to produce a new and improved method for accomplishing the above and a simple and efficient machine for carrying out such method.

Other objects and advantages of the invention will hereinafter appear and, for purposes of illustration, embodiments of the invention are shown on the accompanying drawing, in which:

Figure 1 is a side elevation, partly diagrammatical, of a machine for perforating materials in accordance with this invention;

Figure 2 is an enlarged sectional elevation substantially on the line 2—2 of Figure 1, illustrating the manner in which the material is fed and showing diagrammatically the perforating units, stripper plate and base block or die;

Figure 3 is an enlarged fragmentary vertical section of the perforating units, showing the material in process of perforation;

Figure 4 is a plan view, partly schematic, of a portion of the needle-supporting platen, showing the arrangement of the needles or perforating units;

Figure 5 is an enlarged fragmentary perspective view of a portion of the material after being perforated, showing the irregular, non-mechanical appearing arrangement or pattern of the minute perforations; and

Figure 6 is an enlarged diagrammatic view

showing the manner in which positioning of the needles in the various zones is determined.

The illustrated embodiment of the invention comprises a press 10, the general construction of which is old in the art. The press is provided with a frame 11 having a vertically reciprocatory head 12 actuated by connecting rods 12a driven from a suitable crank shaft on one end of which is mounted a driving wheel 12b. Disposed below the reciprocatory head 12 is a stationary bed 13. 10

As shown, material M is introduced or delivered to the machine between a pair of opposed rollers 14 and is advanced beneath the perforating mechanism to the rollers 15 which are arranged on the opposite side of the machine. The material M to be perforated is relatively thick and tough, such for example as a composite material having a layer of woven textile fabric to which is adhesively secured a layer of rubber, rubber composition, rubber substitute 20 or the like. It is not intended that this invention be restricted to any particular flexible sheet material, but the above will illustrate the character of the material which the machine is particularly adapted to handle. 25

The rollers 14 and 15 or either pair of them, frictionally engage with the material M and are intermittently driven in order to impart a step by step movement to the material. Any well known mechanism may be employed for effecting such intermittent or step by step movement. For example, a well-known ratchet and pawl mechanism may be employed and, as shown, a spring pressed pawl 15a carried by a rod 15b secured to the head 12 of the press is engageable when the head moves upwardly, with a ratchet wheel 15c secured to the upper roll 15 so that each time the head moves upwardly the roll 15 is driven a predetermined extent for advancing the material the desired distance. Preferably the material M should be advanced each time a distance of the order of that designated by the letter X for a purpose which will herein-after be explained. 35

A perforating unit generally indicated by the 45 numeral 25 is attached in any suitable manner to the head 12 of the press and upon each downward movement of the head 12, the material is perforated and after perforation is accomplished the roller arrangement 14 and 15 impart the 50 movement to the material M a distance substantially equal to the distance X.

The perforating unit 25 is composed of an intrusive needle holding platen 26 on which are disposed a great number of intrusive points or 55

needles 27, a portion of which are rigidly fixed to the platen or holding member 26. The points or needles 27 extend through and beyond holes 29 in a stripper plate 28. The holes 29 are disposed respectively in registry with the points or needles 27. The stripper plate operates to strip the material M from the needles 27 when the latter are withdrawn from engagement with the material. Any suitable means may be employed for accomplishing this purpose, springs or cams being suitable, but since this mechanism forms no part of the present invention, detailed description is not considered necessary.

Mounted on the stationary bed 13 of the press 15 is a die or support 29a provided with holes 30, one being provided for each of the needles 27 in alignment therewith so that after the needles have been forced through the material M, as indicated in Figure 3, the same may extend 20 into the openings 30.

To afford adequate support for the material M during the perforation thereof, a partition or wall 31 of substantial thickness is formed in the die 29a between the openings 30. The openings 30 must be somewhat larger than the needles 27 to provide a certain amount of play and to insure that the points will not be broken by coming in contact with a wall of the die. Since the size of the openings 30 must be ample and 30 since there must be a substantial support for the material during the perforation, the spacing of the needles 27 is limited to a degree that insufficient porosity in the material would be secured at one perforating. Consequently it is 35 necessary to compound or increase the number of perforations. For this purpose the needle-supporting platen 26 is divided theoretically into several longitudinal divisions or zones as indicated by the reference characters y, y' and y², 40 each zone extending the full length of the platen 25. The width of each of the zones y, y' and y² equals the material travel X above described.

In operation it will be understood that the needles in the three zones simultaneously perforate the material intrusively while the material 45 is at rest. The material is then advanced by the rollers a distance substantially equal to the distance X, indicated on Figure 2, after the head 12 of the press has first retracted. When the head again lowers the portions of the material 50 previously perforated by the zones y' and y² are then perforated respectively by the zones y and y'. In the next perforating operation the section of the material which had been previously 55 perforated by the zones y² and y' successively is then perforated by the zone y. This compounding of perforations is of importance in that it increases the number of minute pore-like holes in the material to impart the desired 60 "breathing" characteristic.

One feature of particular advantage is in the irregular arrangement of the needles 27 in the zones y, y' and y². For example, the needles in the zone y' are so arranged as to cause perforation in irregular interspersion with the needles in the zone y. This is also true with respect to the needles in the zone y² as compared with those in the zone y' as well as the needles in the zone y² compared with the zone y. It is 65 important that the points in each of the zones y, y' and y² should intersperse irregularly with each other and as a consequence the material will be irregularly perforated in a non-mechanical appearing pattern, such as indicated in Figure 5. The fabric after being perforated in this

manner not only has the desired "breathing" property so that it is admirably adapted for wearing apparel, but the arrangement is such as to embellish the material in such a manner as to simulate the pores of the skin, a feature 5 which is most desirable from a commercial standpoint.

The manner in which the needles 27 are positioned for the various zones y, y' and y² is diagrammatically illustrated in Figure 6. D designates an enlarged section of the material which has already been perforated, possibly containing a certain pattern which it is desired to reproduce in accordance with the method hereinbefore described. The perforations on the section 10 D may be very numerous and it may be desirable to photographically enlarge that section in order to render the perforations more easily discernible. As above mentioned, the distance between the needles 27 in the platen 26 is limited 15 and in working out a plan for the arrangement of the needles, the permissible distance between them must be taken into consideration. This distance is measured and that measurement used as the diameter of a circle, as indicated at 32. 20 Then, by a compass or other suitable tool all adjacent perforations are encircled, care being taken to insure that the circles 32 of one zone do not overlap each other.

For example, the full line circles a shown on 30 Figure 6 represent the positioning of the needles with respect to the zone y, the broken line circles b represent the positioning of the needles for the zone y' and the dotted line circles c represent the positioning of the needles for the zone y². By planning a small section in this manner a large area can be worked out by duplicating the arrangement of the needles thus indicated.

One manner of completing the work would 40 be by punching holes through a sheet of this character of the desired size on to a sheet of paper provided for each particular zone. Guided by that diagram the holes can be readily drilled in the platen 25 to hold the needles in a corresponding manner. It is to be understood that the number of zones is governed by the degree 45 of porosity desired in the finished product so that considerably more than three zones may be employed if a very porous material is desired, but ordinarily the number would not be less than three.

It is to be understood that numerous changes in details of construction, arrangement and operation may be effected without departing from 55 the spirit of the invention, especially as defined in the following claim.

What I claim as new and desire to secure by Letters Patent is:

Machine for intrusively perforating relatively 60 thick and tough materials, such as rubber coated textile fabrics, which comprises a perforating device having a plurality of equal zones of perforating needles, the needles in each zone being arranged in a predetermined irregular manner 65 and the needles in one zone being arranged differently from those in the next succeeding zone, means for pressing said perforating device recurrently against the material for perforating same, and means to intermittently advance the 70 material between perforating steps a distance substantially equal to one dimension of a zone, thereby to intersperse perforations in the material in a predetermined irregular manner.
